APPARATUS FOR KEYING-UP ROLLING MILL HOUSINGS

George Dahlgren, Chicago, Ill., assignor to United States Steel Corporation, a corporation of New Jersey

Application June 7, 1957, Serial No. 664,274

5 Claims. (Cl. 80—55)

This invention relates to apparatus for "keying-up" a rolling mill, i.e., maintaining a tight fit of the parts thereof which determine the setting or adjustment of the spaced housings composing a mill stand.

A mill stand for rolling structural shapes such as H-beams usually comprises a fixed housing and an adjustable housing secured thereto by horizontal tie rods with spacers between the housings. Each of two horizontal rolls is journaled in the two housings and a vertical roll is journaled in each housing to complete the pass. The spacing of the vertical rolls may be changed by moving the adjustable housing but is determined by the spacers between the housings and the latter must be pulled tightly against the spacers to "key up" the stand and eliminate looseness. This has been done heretofore by using U-section spacers or compression sleeves on the overhanging portions of the tie rods and driving through slots in the rods, wedging keys which engage the sleeves. Thermal expansion of the rods or vibration from normal rolling operations may relax the tension in the rods and thereby disturb the adjustment of the housings causing the mill to roll off-gage product.

I have invented power means for keying-up the mill and automatically compensating for thermal elongation of the tie rods, thereby maintaining the tension therein and the tightness of the mill setting. Essentially, my invention comprises means including constantly acting hydraulic motors for exerting tension on the tie rods throughout the rolling operation, to take up and compensate for any looseness which might otherwise result from thermal expansion.

A complete understanding of the invention may be obtained from the following detailed description and explanation which refer to the accompanying drawings illustrating the present preferred embodiment. In the drawings:

Figure 1 is an elevation of a mill stand for rolling wide-flange beams, having the invention incorporated therein, with parts in vertical section and parts omitted;

Figure 2 is an enlarged view partly in section along line II—II of Figure 1 and partly in elevation, the mill stand being omitted; and

Figure 3 is a portion of Figure 1 to enlarged scale.

Referring now in detail to the drawings, and for the present, particularly to Figure 1, a mill stand **S** for rolling wide-flanged beams comprises housings **10** and **11** standing on mill shoes **12**. Housing **11** is secured to the shoes by clamp bolts **13**. Housing **10** is adjustable along the shoes by known means (not shown). When adjusted, it is secured rigidly in spaced relation to housing **11** by tie rods **14** extending horizontally through the housings, and spacer blocks **15** and **16**. Nuts **14a** are screwed on the ends of rods **14** on the outside of housing **11**. The mill stand also includes top and bottom horizontal rolls **17** and **18** journaled in housings **10** and **11** and vertical rolls **19** and **20** journaled one in each housing. The construction described so far is known and further details thereof are unnecessary. My invention

2

concerns only the means for exerting constant tension on rods **14** to key up the stand and keep it in that condition. The details thereof are shown at the left-hand end of Figure 1 and in Figure 2.

5 The outboard ends of rods **14** extend through a structural frame **F** including columns **21** and pairs of transoms **22** and **23** carried thereby. Transoms **22** and **23** carry rectangular slide bearings **24** for nuts **25** and **26**. A sleeve **27** slipped on rods **14** has its ends threaded with 10 screws of opposite pitch and the bores of nuts **25** and **26** are correspondingly threaded. Rotation of sleeves **27** in one direction causes nuts **25** to exert a thrust away from the stand **S** and nuts **26** to exert a thrust toward the stand. The thrust of nuts **25** is applied to keys **28** inserted through slots in the ends of the rods **14** and the thrust of nuts **26** is applied to U-section spacers **29** placed over the rods and bearing against housing **10**. Bearing collars **30** are placed on rods **14** between nut **25** and key **28** and between nut **26** and spacers **29**. Thus the mill stand is keyed up by applying tension to the rods **14** and pressure to spacers **29**, i.e., housing **10** is forced tightly against blocks **15** and **16** and the latter against housing **11**.

The mechanism for actuating the sleeves **27** is shown 20 clearly in Figure 2. Alined double-acting cylinders **31** and **32** having their adjacent ends connected, are mounted on a plate **33** extending between the transoms **22** and **23** on the mill side of the structural frame **F**. Blocks **34** attached to the piston rods of the cylinders are slidable in 25 ways **35** also carried by plate **33**. Equalizer levers **36** are pivoted to the piston rods of the cylinders **31** and **32**. Links **37** and **38** are pivoted to the ends of each lever **36** and to cranks **39** keyed to the sleeves **27** of the tie rods on one side of a vertical plane through the axes of 30 rolls **17** and **18**.

By applying fluid pressure from any convenient source 35 to the rod ends of cylinders **31** and **32**, levers **36** are pulled toward each other causing rotation of sleeves **27** through a limited angle as shown in chain lines, in such 40 direction as to key up the stand. This pressure is maintained throughout rolling operations. Thus, if rods **14** elongate as by thermal expansion, take-up or compensation is effected instantly by the fluid pressure constantly applied to the cylinders, which is effective to maintain a 45 constant tension in the rods. When it is desired to change the setting of the mill by moving stand **10** along shoes **12** and replacing spacer blocks **15** and **16** with others of different length, admission of fluid pressure to a port 50 between the pistons of cylinders **31** and **32**, together with relief of the pressure on the rod ends, will turn sleeves **27** through a limited angle in the reverse direction, removing the tension from tie rods **14** and the pressure from spacers **29**.

It will be apparent that the invention provides simple 55 yet effective means for keying-up a mill stand initially after adjustment, and maintaining the movable housing rigidly in spaced relation to the stationary housing throughout rolling operations despite expansion of the tie rods, by constantly applied fluid pressure exerting tension on the rods and compression on the spacers. The 60 mechanical advantage secured by cranks **39** and screw sleeves **27** permits the desired tension and compression to be established by the use of only relatively low-pressure fluid in cylinders **31** and **32**.

65 Although I have disclosed herein the preferred embodiment of my invention, I intend to cover as well any change or modification therein which may be made without departing from the spirit and scope of the invention.

I claim:

70 1. In a beam-rolling mill, including a pair of upright housings, one fixed and the other movable from and toward the fixed housing, horizontal spacers between said

housings, horizontal tie rods extending laterally from the fixed housing through the movable housing and beyond it and spacer sleeves on the outboard portions of said rods bearing against said movable housing, the combination therewith of means including hydraulic motors adapted constantly to apply tension to said rods and compression to said sleeves, thereby holding said movable housing tightly against said spacers despite thermal elongation of said rods.

2. Apparatus as described in claim 1, characterized by said means including also screw means on each rod effective to apply opposite thrusts to said rods and sleeves, respectively.

3. Apparatus as described in claim 1, characterized by said means including also a screw sleeve rotatable on each rod and a nut in which said sleeve is threaded, engaging one of said rods and its spacer sleeve.

4. Apparatus as described in claim 1, characterized by said means including also a screw sleeve rotatable on each rod having threads of opposite pitch at its ends

and nuts into which said sleeve is threaded, said nuts engaging the rod and its spacer sleeve, respectively.

5. Apparatus as described in claim 4, characterized by a crank arm on each screw-sleeve and means whereby said motor exerts torque on said arms.
